UNITED STATES PATENT OFFICE

JULIUS BRENZINGER, OF FAIRFIELD, CONNECTICUT, ASSIGNOR TO THE MAX AMS CHEMICAL ENGINEERING CORPORATION, OF BRIDGEPORT, CONNECTICUT, A CORPORATION OF CONNECTICUT

WINDING MECHANISM

Application filed June 6, 1930. Serial No. 459,482.

This invention relates generally to winding mechanism, especially of the character used in connection with the winding of newly-formed or green synthetic thread-like material.

In the production of artificial silk or the like, the thread-like material issues from a spinnerette immersed in a bath, and the thus newly-formed or green thread-like material passes then directly to a winding mechanism consisting essentially of a thread-guide and a rotatable spool, said elements having a transverse movement one with relation to the other so that the thread-like material is wound crosswise into a number of superposed series of convolutions first in one direction and then in the other. The wound material is subjected to a washing or dyeing process by drawing liquid through the convolutions of material and into the interior of the spool. For this reason it is now the custom, as disclosed in my application Ser. No. 378,064, filed July 13, 1929, to so wind the material on the spool that the convolutions are slack whereby numerous interstices are formed that facilitate the penetration, by the liquid, of the wound material and shortens the length of time necessary to complete the washing or dyeing process. Such slack also has the advantage that, when the wound material subsequently is subjected to finishing or drying, the shrinkage thereof will not place unequal strains on different portions of the material, which unequal strains would tend to result in a length of material of non-uniform character being produced.

The main object and feature of this invention is to produce a simple and inexpensive mechanism whereby the newly-formed or green thread-like material may be wound into convolutions having slack which, if desired, may be of a highly irregular character.

In the accompanying drawings the invention is disclosed in a concrete and preferred form in which

Fig. 1 is a top plan view of winding mechanism embodying the invention;

Fig. 2 is a view in side elevation of the parts disclosed in Fig. 1 with the reciprocatory member shown in the middle of its stroke;

Fig. 3 is a view similar to Fig. 2, but less complete, showing the reciprocatory member at one end of its stroke; and

Figs. 4 to 7 inclusive are diagrams showing some typical slack formation in the wound thread-like material.

1 indicates a thread-guide and 2 is a rotatable spool mounted on shaft 3 receiving motion from shaft 4 by means of gears 5. Suitable means are provided to effect a relative traverse movement of the guide and spool one with respect to the other. In the present instance, the thread-guide is reciprocated with respect to the spool so as to lay the thread-like material in superposed layers first in one direction and then in the other as is well understood. In the form of the invention shown, 6 indicates a reciprocatory member sliding on upper and lower guides 7, said member 6 carrying thread-guide 1. 8 indicates a rotatable member carrying a mutilated gear 9 that meshes alternately with upper and lower rack 10 and 11 of member 6. Associated with the reciprocatory and rotatable members is a cam and roll connection to complete, reverse and initiate the stroke of the reciprocatory member. As here shown cams 12 and 13 are mounted on member 6 and roll or pin 14 is carried on an arm 15 of member 8 or gear 9. Assuming the parts to be in the position shown in Fig. 2 and member 8 to be rotating clockwise, it will be seen that member 6 will be moved to the left in the figure and that eventually the mutilated gear will disengage rack 11. At about the time this occurs, roll 14 will have engaged cam 13 and will continue the movement of member 6 until the position of the parts shown in Fig. 3 is reached when the cam and roll will reverse the stroke and initiate the movement of member 6 in the opposite direction, and, at about the time roll 14 disengages cam 13, gear 9 will engage rack 10 and continue the movement until roll 14 engages cam 12. It is, however, desired to lay the thread on the spool with a considerable slack and the following expedients are therefore resorted to. Rotatable member 8 is provided with a ratchet 15 which is driven by a pawl 16 mounted on crank 17. Crank 17 is rotated continuously

by any suitable means such as sprocket 18 and chain 19 reaching from sprocket 20 on shaft 21. In this fashion member 8 is given an intermittent movement and member 6 is given its traverse movement in the form of a series of intermittent steps first in one and then in the other direction. In addition the thread guide is vibrated, and specifically here oscillated, preferably a plurality of times to each traverse movement of member 6. In the present instance, this is accomplished by mounting the thread-guide on a pivot 22 and by rocking said pivot by means of arm 23 and connection 24 from crank 25 carried by sprocket 26. Sprocket 26 is rotated by chain 27 trained around sprockets 28 and 29, the latter of which is carried by rotating shaft 21. The bearing, 30, of sprocket 26 is carried by member 6. It will therefore be understood that the thread-guide is oscillated about center 22, and that, in the present instance, this oscillation is continuous, and that the traverse of member 6 is caused by a series of intermittent steps. The lay of the thread will, of course, vary with the gear ratio of the parts but in Figs. 4 to 7 inclusive are shown some typical lays of the thread. In these diagrams the length of line *a* represents one revolution of the spool and *b* is the thread. The sharp deflection *c* indicates the result of an intermittent step of member 6 and the wavy connecting lines *d* indicate the effect of the oscillation of the thread guide. In this example therefore, there is a plurality of intermittent steps and a plurality of oscillations during a single revolution of the spool. In Fig. 5 there is shown the effect of a plurality of intermittent steps at *c* and of a single oscillation of the thread-guide at *d*. In Fig. 6, the effect of a single intermittent step is shown at *c* and of a single oscillation at *d*. In Fig. 7, the effect of a single intermittent step is shown at *c* and a plurality of oscillations is shown at *d*.

I claim:

1. Winding mechanism for thread-like material including: a thread-guide, a rotatable spool, a reciprocating member carrying the thread-guide, opposed racks on said reciprocating member, a rotatable member, a mutilated gear on said rotatable member to alternately engage the racks, a cam and roll connection associated with said reciprocating and rotatable members, to complete, reverse and initiate the stroke of the reciprocating member, and means to intermittently rotate the rotatable member.
2. Winding mechanism for thread-like material including: a thread-guide a rotatable spool, a reciprocating member carrying the thread-guide, opposed racks on said reciprocating member, a rotatable member, a mutilated gear on said rotatable member to alternately engage the racks, a cam and roll connection associated with said reciprocating

and rotatable members, to complete, reverse and initiate the stroke of the reciprocating member, and a ratchet-and-pawl connection to intermittently rotate the rotatable member.

3. Winding mechanism for thread-like material including: a thread-guide, a rotatable spool, a reciprocating member carrying the thread-guide, opposed racks on said reciprocating member, a rotatable member, a mutilated gear on said rotatable member to alternately engage the racks, a cam and roll connection associated with said reciprocating and rotatable members, to complete, reverse and initiate the stroke of the reciprocating member, and means to oscillate the thread-guide a plurality of times to each reciprocating movement of said member.

Signed at Bridgeport, in the county of Fairfield and State of Connecticut, this 29th day of May, 1930.

JULIUS BRENZINGER.
